Specification for Design.

Patented May 7, 1918.

Application filed March 16, 1917. Serial No. 155,365. Term of patent 3½ years.

To all whom it may concern:

Be it known that I, JOSEPH A. FRANKLIN, a citizen of the United States, residing at Chicago, in the county of Cook and State of Illinois, have invented a new, original, and ornamental Design for Dispensing-Urns, of which the following is a specification, reference being had to the accompanying drawing, forming part thereof.

The figure is a perspective view of a dispensing urn, showing my new design.

I claim:

The ornamental design for a dispensing urn, as shown.

JOSEPH A. FRANKLIN.
